UNITED STATES PATENT OFFICE.

CHRISTIAN PEPER, OF ST. LOUIS, MISSOURI.

CABLE RAILWAY.

SPECIFICATION forming part of Letters Patent No. 372,866, dated November 8, 1887.

Application filed May 23, 1887. Serial No. 239,119. (No model.)

To all whom it may concern:

Be it known that I, CHRISTIAN PEPER, of the city of St. Louis, in the State of Missouri, have invented a certain new and useful Improvement in Cable Railways, of which the following is a full, clear, and exact description, reference being had to the accompanying drawings, forming part of this specification, and in which—

10 Figure I is a top or plan view showing a section or portion of my improved railway. Fig. II is a transverse vertical section taken on line II II, Fig. I. Fig. III is a transverse section through the road at one of the wells 15 that connect with the sewer. Fig. IV is a perspective view of one of the chairs. Fig. V is a similar view showing a slight modification of a chair which is more particularly intended to be used at the joints of the yoke. Fig. VI is a 20 detail section showing a modification. Fig. VII is a detail vertical section.

My invention relates to certain improvements in cable railways; and it consists in features of novelty, hereinafter fully described, 25 and pointed out in the claims.

Referring to the drawings, 1 represents the road-bed, 2 the track-rails, and 3 the conduit, of a cable railway.

My invention relates to the chairs for supporting the conduit and the manner of securing the conduit to the chairs.

4 represents one of the chairs made as shown in Fig. IV, consisting, preferably, of two triangular pieces or standards connected by a web 35 or portion, 5.

Each standard of the chair is preferably made double, the two parts being slightly separated and preferably connected together both by a web, 7, at bottom and the block 10, hereinafter 40 described, at top.

The conduit is made in two portions of inverted-L shape in cross-section, one portion fitting against each inner wall, 6, of the chair, as shown in Fig. II.

45 The web 5 of each chair is provided with flanges or lugs 7, between which and the walls or faces 6 of the chair the lower edges of the conduit-plates fit, as shown in Fig. II, and are held from lateral movement. The conduit- 50 plates are connected to the upper portion of the chair by means of rods 8, passing through perforations 9 in blocks 10, the blocks fitting

in notches 11 of the chair and having notches 12, which fit under projections 13 above the notches 11. Beneath the notches 11 are flat 55 surfaces 14 on the chairs, upon which the bottoms of the blocks fit. The blocks are thus held from lateral movement on the chairs by the tongues or projections 13, fitting in the notches 12, and they are held from vertical 60 movement by the tongues 13 and the shoulders or surfaces 14. The bolts 8 firmly connect the yokes to the blocks; and it will be seen that for the frost to close the slot of the yoke by the expansion of the street, it will be necessary for 65 it to bend or break the chairs, which, if made strong, as they should be, it is thought will be practically impossible. In case it is desired to remove a section of the conduit, it is only necessary to remove the nuts from the bolts 8, 70 when the blocks 10 can be pulled off the bolts and then a section can be lifted up. With this arrangement the conduit-sections can be cheaply and durably held in place.

In Fig. V, I have shown a form of chair intended primarily to be used at the joints of the conduit sections, the difference between this and the main form being that the two walls of each side of the chair are connected by means of a cross web or portion, 17, which would be 80 slotted at 18 for the passage of the bolts 8; and with this arrangement the blocks 10 could be dispensed with, the heads of the bolts fitting against the outer walls of the webs or portions 17.

85 In Fig. VI, I have shown another modification, wherein the blocks 10 are dispensed with and the bolts 8 are passed directly through the vertical walls of the chairs. This section is taken on line VI VI, Fig. V, with the perforations for permitting the passage of the bolts added, and the walls of the chair also made thicker to give the necessary strength where such holes are used.

It will be seen that there is no connection 95 whatever between the conduit and the road-bed, so that the former can be removed at any time without disturbing or interfering with the latter.

In Fig. VII, I have shown a track-chair, 19, to be attached to the chair 4 by means of a bolt, 20, or by other suitable means, and have shown plates 21, within the track-chair, over which a plate, 22, may rest, and on top of this the track-

rail may be placed. This manner of supporting the rails may be used, if desired, in lieu of the chairs 4.

I claim as my invention—

- 5 1. A chair for supporting the tube or conduit irons, having on each side two pieces forming standards connected together, the double standards on both sides being further connected together by a web, substantially as set forth.
- 10 2. The combination of the tube or conduit plates, a chair having its two sides connected by a web and each side having two parts or standards, a connection between the two parts or standards on each side, and bolts uniting said connection to said slot or conduit plates, substantially as set forth.

3. In a cable railway, in combination with a tube or conduit, a chair, 4, consisting of two portions, blocks fitting in the upper ends of the 20 chair, and bolts connecting the tube structures to the chairs by passing through perforations in the blocks, substantially as and for the purpose set forth.

25 4. In a cable railway, in combination with a tube or conduit, a chair made in two portions,

notches forming shoulders 14, and projections 13 on the chair, notched blocks fitting in the notches of the chair, and bolts connecting the tube or conduit to the chair by passing through perforations in the blocks, substantially as set 30 forth.

5. In a cable railway, in combination with the tube or conduit plates, a chair formed of two triangular portions connected by a web, 35 notches 11 in the upper portions of the chair, forming shoulders 14, and projections 13, blocks having notches 12 and perforations 9, and bolts passing through the perforations in the blocks and connecting the tube or conduit plates to the chair, substantially as and for the 40 purpose set forth.

6. In a cable railway, in combination with the chairs 4 and tube or conduit plates 3, made substantially as described, track-chairs 19, plates 21 and 22, and track-rails 2, substantially as set forth. 45

CHRISTIAN PEPPER.
